KITCHEN CANISTER

Louis Stahl, New York, N. Y.

Application July 6, 1951, Serial No. 15,781

Term of patent 14 years

(Cl. D44—6)

To all whom it may concern:

Be it known that I, Louis Stahl, a citizen of the United States, residing in New York city, county of Bronx, State of New York, have invented a new, original, and ornamental Design for a Kitchen Canister, of which the following is a specification, reference being had to the accompanying drawing, forming a part thereof, in which:

Fig. 1 is a top plan view of a kitchen canister, showing my new design;

Fig. 2 is a front elevational view thereof, the sides and rear being a duplicate of the front with the exception that no lettering appears thereon;

Fig. 3 is a bottom plan view thereof; and

Fig. 4 is a vertical cross-sectional view, taken along line 4—4 of Fig. 1.

I claim:

The ornamental design for kitchen canister, as shown and described.

LOUIS STAHL.
